UNITED STATES PATENT OFFICE.

PHILIP HUSTA, OF CORONA, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed September 7, 1921. Serial No. 499,101.

To all whom it may concern:

Be it known that I, PHILIP HUSTA, a citizen of the United States, residing at Corona, in the county of Queens, State of New York, ⁵ have invented certain new and useful Improvements in Signaling Systems, of which the following is a full, clear, concise, and exact description.

This invention relates to signaling systems and more particularly to methods and means for transmitting to a calling subscriber's station an audible ringing signal to indicate that the called subscriber's station is being signaled.

¹⁵ In some circuits of this nature the character of the signaling tone which the calling subscriber hears while waiting for the called subscriber to answer is subject to considerable variation, due to a number of causes. Heretofore it has been the usual practice to obtain the signaling tone by completing the ringing circuit of the called subscriber's station through one winding of the repeating coil of the connecting link ²⁰ circuit, the tone that the calling subscriber hears being obtained by induction through the windings of the repeating coil. This tone is due to the audible higher harmonics of the ringing current and it is found that ²⁵ these generally differ with each source of ringing current supplied. Another variation is caused by the variable volume of the ringing current due to lack of uniformity in the resistance of the called subscriber's line; in the case of long lines the tone is weak, and the opposite is true for short lines. Again, the tone varies with the number of subscribers in the same central office being simultaneously signaled and with the ³⁰ voltage of the source of ringing current.

It is an object of this invention to provide methods and means for employment preferably in present equipments to furnish an audible ringing signal wherein the disadvantages described above are avoided, and further to attain this without destroying the electrical continuity of the calling and the called ends of the link circuit, so as to avoid any extensive or disturbing change ⁴⁵ in such equipments.

To attain this object in accordance with one feature of the invention a separate source of signaling current is provided. This current is generated in a circuit of ⁵⁰ comparatively high impedance. In this cir-

cuit is also located a low impedance section, and through this section there is also passed the regular ringing current as well as the audible ringing signal current. Because of the constancy of the potential drop of this ⁶⁰ audible ringing signal current across the low impedance section a substantially constant tone is supplied to the calling subscriber irrespective of variations in the character of the regular ringing current used to signal ⁶⁵ the station of the called subscriber and which may be due to the causes outlined above.

For a more complete understanding of the invention reference may be had to the ⁷⁰ following description in connection with the accompanying drawing Fig. 1 of which illustrates one embodiment of the invention and Figs. 2, 3 and 4 of which show, respectively, the wave forms of the output of the ⁷⁵ ringing generator, of the signaling current transmitted to the calling subscriber in one of the above mentioned systems widely in use and of the signaling current transmitted to the calling subscriber in accordance with ⁸⁰ the embodiment of the invention shown in Fig. 1.

The drawing shows two subscribers' stations A and B connected by a link circuit L, which link circuit is arranged in the ⁸⁵ manner well known, to automatically supply to the called station B ringing current from a source 1. While the station B is being signaled, a portion of ringing current passes to ground through the upper right-hand ⁹⁰ winding of a repeating coil 2, and another portion to ground through a low impedance path through the resistance 3 by way of the upper alternate contact of ringing relay 4 which is actuated when the plug 5 is inserted into the jack 6. Owing to the low impedance of the path through resistance 3 only a small volume of the audible components of the ringing current from source 1 is ⁹⁵ passed through the comparatively higher impedance path of the repeating coil winding. However, a high speed interrupter 7 in series with grounded battery supplies to the path ¹⁰⁰ 3 through the contacts of a relay 8 and the windings of a transformer 9 and its associated apparatus a volume of audible ringing signal current many times greater than that obtained from the audible components of source 1. This preponderance of ringing signal current from the interrupter circuit ¹⁰⁵ 110

renders the signaling tone furnished to the calling subscriber's station A substantially constant independent of the variations of current from the source 1.

5 As shown in Fig. 2 the current produced by the source 1 possesses numerous harmonics which affect the wave form of such current. As previously mentioned, in one system widely in use the higher of such harmonics superimposed upon the 16-cycle current are transmitted to the calling subscriber through a repeating coil similar to repeating coil 2. In such a case the current wave flowing over the calling line assumes, 10 in general, the resultant of the wave forms shown in Fig. 3. Although there may be many more harmonics present, only a sufficient number have been shown to illustrate the form produced. This current has been 15 found to produce a distinctive and pleasing tone in the calling subscriber's receiver. The current produced by means of the battery, the commutator, the repeating coil 9 and other associated apparatus is of a single 20 unmodulated frequency as shown in Fig. 4. The frequency of this latter current has been selected to correspond with one of those which predominate in the wave shown in Fig. 3 and therefore such current produces a distinctive constant tone in the calling subscriber's receiver which is entirely 25 independent of any variations in current produced by the ringing current source 1.

It is thought that the invention may be 30 more fully comprehended from the following detailed description of the operation of the circuit.

Assuming that the subscriber of station A desires a conversational connection with 35 the subscriber of station B whose line is one of a plurality of similar lines terminating at a switchboard in the same office with the line of subscriber A or in a distant office, and that a connection with the calling 40 subscriber A has been established in the usual way, the operator in the well-known manner completes the connection desired by inserting plug 5 of the link circuit L into jack 6. An operative circuit for relay 4 is 45 then completed which may be traced from grounded battery, through the winding of relay 4, contact of marginal tripping relay 10, right-hand contact of relay 11, (said contacts short circuiting the winding of relay 11), sleeve contacts of plug 5 and jack 6, and resistance 12 to ground. Ringing 50 current from source 1 is now supplied to the subscriber's station B over the following path: source of ringing current 1, collector 55 ring 13, conducting segment 24 of interrupter 14, winding of relay 10, which does not operate until the subscriber of station B responds, lower alternate contact of relay 4, ring contacts of plug 5 and jack 6, apparatus 60 of station B, tip contacts of jack 6

and plug 5, and then to ground through parallel paths comprising the upper right-hand winding of repeating coil 2 and the resistance 3, the latter path by way of the upper alternate contact of relay 4.

The subscriber of station A listening for the subscriber at station B to answer, hears but a small volume of tone due to the audible components of the ringing source 1, by reason of the marked shunting effect of the 70 low impedance path through resistance 3. However, when the brush of interrupter 14 is in contact with the segment 24, relay 8 is energized over an obvious circuit which 75 includes the condenser 15. This causes interrupted battery current to be supplied over a circuit from grounded battery, interrupter 7, contact of relay 8, and to ground through the primary windings 16 of the 80 transformer 9. In shunt with these windings 16 are a resistance 17 and a condenser 18 so designed as to prevent sparking at the brushes of the interrupter 7 and to improve the wave form of the output. The 85 interrupter and associated circuits are designed to supply signaling current of any convenient audible frequency. The effect 90 of this arrangement is to supply through the secondary winding 19, coil 20 and condenser 21, a current of audible frequency. 95

From the upper terminal of resistance 3 a circuit may be traced through the upper alternate contact of relay 4 and the upper right-hand winding of repeating coil 2 to ground. Accordingly the potential drop 100 across resistance 3 is effective in producing by induction through the windings of repeating coil 2, the transmission of a signaling tone to station A. The volume of this 105 tone can conveniently be made many times greater than the volume of tone due to the higher harmonic components from the source of ringing current 1. Therefore, the character of this tone depends principally 110 upon the frequency of the interrupter 7 and is practically independent of the tone due to source 1, as appears from the following.

If the resistance of the line of a called 115 station B varies, it is obvious that the volume of current from source 1 passing through the upper right-hand winding of the repeating coil 2 also varies accordingly. Similarly there is a current variation 120 depending upon the voltage of the current of source 1 and upon the number of called stations being signaled simultaneously over the conductors 22, 23, leading to other link circuits similar to link circuit L. There is also a variation in signaling tone from 125 source 1 depending upon the magnitude of its audible harmonic components. However, all these possible sources of variation are without effect by reason of the preponderating effect of the tone from interrupter 7. The low impedance path through 130

resistance 3 has the desirable characteristic of effectively shunting away from the winding of the repeating coil 2 ringing current from source 1, and by reason of its low 5 impedance compared to the impedance of the apparatus with which it is in series and of the multiple paths through the upper right-hand windings of the repeating coils of other link circuits, an unappreciable 10 change in the potential drop across it results by reason of a variation in the number of called stations being signaled.

Inasmuch as the link circuit L shown on the drawing is well known in the art and is 15 not part of this invention, only so much thereof as is necessary to an understanding of the invention has been disclosed and described herein. The circuit arrangements employed at stations A and B have been 20 omitted since they may be of any usual type.

What is claimed is:

1. In a telephone exchange system, a calling subscriber's station, a called subscriber's 25 station, a link circuit for interconnecting said calling and called stations, a source of signaling current of variable voltage for signaling the called subscriber's station, a second source of signaling tone current for 30 signaling the calling subscriber's station that the called subscriber's station is being called, and a relay operated by current from said first mentioned source for transmitting from said second source of signaling current 35 to said calling subscriber's station a volume of signaling tone substantially independent of variations in the voltage of said first mentioned source of signaling current.

2. In a telephone exchange system, a calling subscriber's station, a called subscriber's station, a link circuit for interconnecting said stations, a source of signaling current for calling the called subscriber's station, said source of current having harmonic components 45 of audible frequency, a source of signaling tone current for signaling the calling subscriber's station that the station of the called subscriber is being called, and means for transmitting from said source of signaling tone current to said calling subscriber's station, a volume of signaling tone substantially independent of variations in the harmonic components of the said first mentioned source of signaling currents, the electrical 50 continuity of the link circuit between the calling and called subscribers' stations being maintained while the called subscriber's station is being called.

3. In a telephone exchange system, a plurality of calling subscribers' stations, a plurality of called subscribers' stations, a plurality of link circuits for interconnecting calling and called stations, a source of signaling current of variable voltage for calling 60 called subscribers' stations, a source of

signaling tone current for signaling each of said calling subscribers' stations that the station of the corresponding called subscriber is being signaled, and means for transmitting from said source of signaling tone current to each of said calling subscribers' stations a signaling tone substantially independent of the total number of said called subscribers' stations being signaled simultaneously, the electrical continuity of the link circuits between the said calling and called subscribers' stations being maintained while the called subscribers' stations are being called.

4. In a telephone exchange system, a calling subscriber's station, a called subscriber's station, a link circuit for interconnecting said stations, a source of ringing current for signaling the called subscriber's station, a source of signaling tone current to signal the calling subscriber's station that the called subscriber's station is being called, a high impedance local circuit for said source of signaling tone current including a low impedance section, means for completing a ringing circuit for the called subscriber's station through said low impedance section, means for using the potential drop across said low impedance section to supply to the calling subscriber's station audible ringing tone of a volume substantially constant and independent of the effect of variations in said source of ringing current, the electrical continuity of the link circuit between the calling and called subscriber's station being maintained while the called subscriber's station is being called.

5. In a telephone exchange system, a calling subscriber's station, a called subscriber's station, a link circuit for interconnecting said stations, a source of signaling current of variable voltage for signaling said called subscriber's station, a source of audible signaling tone resident in said source of signaling current as audible higher harmonics thereof, a source of signaling tone current for signaling the calling subscriber's station that the station of the called subscriber is being called, and means for transmitting from said source of signaling tone current to said calling subscriber's station a volume of signaling tone substantially independent of the variations in the volume of the higher harmonic components resident in the first mentioned source of signaling current, the continuity of the link circuit between the stations being maintained while the called subscriber's station is being called.

6. A telephone system comprising a calling and a called station, a source of ringing current connected thereto, and means comprising a relay responsive to current from said source for sending a tone to said calling station.

7. A telephone system comprising a call-

- ing station, a called station, a source of ringing current electrically connected to both of said stations, a shunt path between said source and said calling station for reducing the intensity of the ringing current supplied to said calling station, and a separate source of ringing current for said calling station.
8. A telephone system comprising a calling and a called station, a source of ringing current connected to the called station, a source of ringing signal current, and a relay responsive to the current supplied from the first named source for connecting the current from the second named source to the calling station.
9. A telephone system comprising a calling station, a called station, a source of ringing current connected thereto, a second source of ringing current, and a relay responsive to current supplied by one of said sources for connecting said other source to the calling station.
10. The method of signaling to calling stations which comprises supplying to each

of said stations signaling current of substantially the same intensity and independent of the length of the called subscriber's loop.

11. A telephone system comprising a plurality of stations, a plurality of sources of signaling current, a plurality of paths for supplying signaling current from said sources to said stations, and means responsive to current in one of said paths for controlling another of said paths.

12. A telephone system comprising a calling line, a called line, a distinct source of signaling current for each of said lines, a plurality of paths for supplying signaling current from said sources to said lines, and a relay included in and responsive to current in one of said paths to control the current in another of said paths.

In witness whereof, I hereunto subscribe my name this 31st day of August A. D., 1921.

PHILIP HUSTA
